UNITED STATES PATENT OFFICE.

EDWARD WICKS, OF BROOKLYN, NEW YORK.

DOOR-CHECK.

SPECIFICATION forming part of Letters Patent No. 390,274, dated October 2, 1888.

Application filed July 13, 1886. Serial No. 207,865. (No model.)

To all whom it may concern:

Be it known that I, EDWARD WICKS, a subject of the Queen of Great Britain, and a resident of the city of Brooklyn, county of Kings, 5 and State of New York, have invented a certain new and useful Safety Stop and Lock for Doors, Windows, &c.; and I hereby declare the following to be a description of said invention in such full, clear, concise, and exact terms as to 10 enable any skilled person to make and use the same, reference being had to the accompanying drawings, wherein like letters of reference indicate corresponding parts throughout the several views.

15 The chief object of my invention is to provide a safety stop and lock for use, separate or combined, of strong and simple construction, novel shape, and especially safe.

In the drawings, Figure 1 shows a plan of 20 the stop and lock combined. Fig. 2 shows a central section of the same, and Fig. 3 is a diagram showing its operation upon an open door.

The stop consists of a T-shaped bar, A, with narrow shank B, hinged at C upon a plate, D, 25 fastened upon the door or window frame or other fixed object I, so that the narrow shank B will swing in between the companion catches G G upon the plate E, correspondingly fastened upon the door or window or other object 30 H, moving open. The length of the narrow shank B will of course depend upon the proximity of the plates D and E, and the closer together they can be put conveniently the less opening will be required to bring the broad T- 35 bar A within the catches G G, which contain the bar, and effectually prevent any one pushing it out. When the door H is opened to the limit of the stop, the top or arms J J of the T- bar hold against the catches G G and the door 40 may be left in such open position with perfect

safety. The material used may be varied and ornamented to suit particular tastes and uses.

The lock consists of the catch F upon the plate E, fitted to enter and engage the slot K in the T-bar A when the door is closed and the 45 bar flat against it. Figs. 1 and 2 show this operation most plainly. These slots may be placed in a series along the bar with advantage where the moving object slides and different degrees of opening secured.

50 The stop and lock may be used together in combination, as shown, or only the stop may be used and the lock omitted, as desired.

What I claim as my invention, and desire to 55 secure by Letters Patent, is—

1. As a safety-stop for doors, windows, &c., a T-shaped bar with narrowed shank hinged upon the fixed object, in combination with two straight rigid catches with inturned ends, one on each side of said bar, and fixed upon the 60 moving object at an outward angle of about forty-five degrees, all constructed and co-operating in the manner and for the purpose substantially as specified.

2. As a combined safety stop and lock for 65 doors, windows, &c., a T-shaped bar with narrowed shank hinged upon the fixed object, in combination with companion catches at an outward angle, and a single catch at right angles between and behind the others, fixed upon the 70 moving object, said bar being provided with a single slot or series of slots along its length, adapted to fit over and hold against the single catch, in the manner and for the purpose substantially as specified.

EDWARD WICKS.
